UNITED STATES PATENT OFFICE.

OSCAR PALMER, OF NEW YORK, N. Y.

AIRPLANE.

Application filed February 3, 1928. Serial No. 251,497.

This invention relates to airplanes and has for an object an airplane structure which provides a back air pressure for the propeller to work against, thereby increasing the speed of the airplane.

According to this invention the fuselage of the airplane comprises a tubular longitudinal member to which are attached wings. The propeller is mounted within the tubular member adjacent its forward end so that the air pushed backwardly by the propeller passes through the tubular member. This arrangement provides a back air pressure for the propeller to work against, which back pressure is not present in the ordinary type of airplane and the speed of the plane is thus increased. Cockpits for the aviator and navigator are provided in the tubular member near its front end and a cabin for passengers and fuel is suspended from the tubular member at its ends.

Other objects, novel features and advantages of this invention will be apparent from the following specification and drawings 25 wherein:

Figure 1 is a plan view of an airplane embodying the invention.

Fig. 2 is a rear view thereof.

Fig. 3 is a front view and Fig. 4 is a side 30 view thereof.

The fuselage 10 comprises a tubular body to which are attached near its front end the wings 11 which extend at right angles to the axis of the tubular member 10. At the ends 35 of the body 10 are provided wheels 12 for use in taking off and landing, these wheels corresponding to the usual landing gear of an airplane. A propeller 13 is mounted on a shaft co-axial with the tubular member 10 and is arranged within such tubular member 40 at the front end thereof. An engine for driving the propeller 13 is located just to the rear of the propeller. The propeller 13 is just enough less in diameter than the interior of the tubular member 10 that it clears the same when rotating. Cockpits 15 and 16 for the aviator and navigator respectively are provided, these cockpits preferably being located adjacent the wings 11. At the rear 45 end of the body 10 is provided a rudder 17 and an elevator 18 the operation of which is controlled by the aviator from his cockpit in the usual manner. A cabin 19 for passengers, fuel and supplies is suspended from 50 the body approximately the middle thereof.

Stationary laterally extending stabilizers 20 are attached to the rear end of the body.

In the embodiment of the invention above described the propeller 13 pushes back through the tubular member of the airplane 60 the air which it displaces. Since the air is confined within the tubular member a back pressure develops, against which the propeller works. As the propeller has such back pressure to work against it is more effective 65 in driving forward the airplane and the speed thereof is increased. The amount of air drawn in by the propeller may be limited by providing at the front end of the body a 70 cagelike member 21. By means of the rudder 17 and the elevator 18 vertical and horizontal direction of movement of the airplane may be controlled. The cagelike member also serves as a protection for the propeller and gives a finished appearance to the airplane. 75

Preferably the airplane is constructed of metal such as duraluminum which is extremely light and very strong. Not only is the body 10 and the cabin 19 to be constructed of this metal but the wings may likewise be 80 formed from the same metal.

Although the propeller 13 has been disclosed as located within the tubular member 10, it is apparent that it might also be supported a short distance in advance of the 85 front end of such member and substantially the same results be obtained. Moreover it is apparent that various structural modifications may be made in the airplane herein disclosed without in any way departing from 90 the spirit of the invention as defined in the appended claims.

I claim:

1. In an airship of the heavier than air type, a fuselage comprising a longitudinal continuous tubular member, wings connected directly to said tubular member adjacent the front end thereof and extending laterally from said member, a propeller rotatably supported within said tubular member adjacent the front end thereof, a driving engine for said propeller within said tubular member and closely adjacent the propeller, said tubular member being unobstructed rearwardly of the engine, a cockpit above said tubular member and supported thereby adjacent the front end thereof and a cabin suspended from said tubular member rearwardly of the cockpit. 95

2. In an airship of the heavier than air 100

type, a fuselage comprising a longitudinal continuous tubular member, wings connected directly to said tubular member adjacent the front end thereof and extending laterally from said member, a propeller rotatably supported within said tubular member adjacent the front end thereof, a driving engine for said propeller within said tubular member and closely adjacent the propeller, said tubular member being unobstructed rearwardly of the engine, a cockpit above said tubular member and supported thereby adjacent the front end thereof, a cabin suspended from said tubular member rearwardly of the cockpit, and a cage like member supported at the front end of said tubular member.

3. In an airship of the heavier than air type, a fuselage comprising a longitudinal continuous tubular member, wings connected directly to said tubular member adjacent the

front end thereof and extending laterally from said member, a propeller rotatably supported within said tubular member adjacent the front end thereof, a driving engine for said propeller within said tubular member and closely adjacent the propeller, said tubular member being unobstructed rearwardly of the engine, a cockpit above said tubular member and supported thereby adjacent the front end thereof, a cabin suspended from said tubular member rearwardly of the cockpit, a cage like member supported at the front end of said tubular member, an elevator supported rearwardly of and in alignment with said tubular member and stabilizers extending laterally from the rear end of said tubular member.

In testimony whereof, I have signed my name to this specification.

OSCAR PALMER.
